(57) **CLAIM**

The ornamental design for a wind turbine tower, as shown and described.

DESCRIPTION

1.1 is a side view of a first embodiment of a wind turbine tower;

1.2 is a front, side perspective view of the wind turbine tower of 1.1;

1.3 is an another front, side perspective view of the wind turbine tower of 1.1;

1.4 is a top view of the wind turbine tower of 1.1;

2.1 is a side view of a second embodiment of a wind turbine tower;

2.2 is a front view of the wind turbine tower of 2.1;

2.3 is a front, side perspective view of the wind turbine tower of 2.1;

2.4 is a top view of the wind turbine tower of 2.1;

3.1 is a front view of a third embodiment of a wind turbine tower;

3.2 is a perspective view of the wind turbine tower of 3.1, turned by 45 degrees;

3.3 is another perspective view of the wind turbine tower of 3.1, turned by 45 degrees; and

3.4 is a top view of the wind turbine tower of 3.1.
